UNITED STATES PATENT OFFICE.

EGMONT B. ARNOLD, OF MILWAUKEE, WISCONSIN.

PUBLICATION-BINDER.

948,125.

Specification of Letters Patent.

Patented Feb. 1, 1910.

Application filed February 6, 1909. Serial No. 476,360.

To all whom it may concern:

Be it known that I, EGMONT B. ARNOLD, a citizen of the United States, and resident of Milwaukee, in the county of Milwaukee and 5 State of Wisconsin, have invented certain new and useful Improvements in Publication-Binders; and I do hereby declare that the following is a full, clear, and exact description thereof.

10 My invention consists in what is herein-after particularly set forth with reference to the accompanying drawings and pointed out in the claims of this specification, its object being to provide simple, economical, 15 strong, durable, convenient and efficient binders especially designed for periodical publications, particularly single publications such as telephone directories.

Figure 1 of the drawings represents an 20 end elevation of a publication binder in accordance with my invention partly in transverse section on the plane indicated by line 1-1 in the second figure of the series; Fig. 2, a plan view of the binder open and partly in 25 section, and Fig. 3, a side elevation of a fragment of said binder partly in section.

Referring by numerals to the drawings, 4 indicates each of the sides and 5 the flexible back of the binder-cover, this cover being of 30 ordinary construction common in the art. Pasted to the back and sides of the cover is a sufficiently wide strip 6 of buckram or other suitable pliable textile fabric folded to form parallel longitudinal 35 pockets 6' for the reception of bows 7, 7' that result from suitable bending of flat metal strips. The bow 7 is inserted at one end of the pockets 6' and the bow 7' is inserted at the opposite end of said pockets, said bows 40 being lapped one upon the other in working position and preferably fastened by any suitable means in the aforesaid pockets that are thereby stiffened. The bend in each bow is centrally provided with an elongated 45 angular eye or slot transversely thereof through which to extend a thin flat strip 8, one end of the strip being preferably bent to form a right-angle stop and the other end provided with an aperture for a hanger-ring 50 9 or other suitable keeper. The space between the pockets 6, 6' and corresponding extent of bend of the bows 7, 7' is immate-

rial as is also the number of slots in each bow-bend and the number of strips 8, these being matters that depend upon the demands 55 of the trade.

The publication to be bound is set in between the pockets 6', as shown by dotted lines in Fig. 1, the strip 8, positioned as herein shown, being then engaged with said 60 publication as well with the bends of the bows 7, 7', and the hanger-ring 9 or other keeper is engaged with said strip to prevent retraction of same.

By the employment of the thin, flat strip 65 8, as aforesaid, the bound publication has no tendency to bulge when closed, said strip being close fitting between leaves of said publication.

I claim:

1. A binder-back having parallel pockets 70 of textile fabric thereon longitudinally thereof, bows resulting from bending of flat metal strips engaging the pockets from opposite ends of same and lapped one upon the 75 other to stiffen said pockets, a removable strip extending through slots in the bow-bends, and means for maintaining the strip in its engagement with said bow-bends.

2. A binder-back having parallel pockets 80 thereon longitudinally thereof, bows resulting from bending of flat metal strips engaging the pockets from opposite ends and having exposed elongated angular eyes in the 85 bends, a thin flat metal strip extending through said eyes, and means for maintaining the strip in engagement with said bows.

3. A binder back, a single strip folded to form a plurality of parallel pockets longitudinally of the back to which it is secured, 90 bows engaging the pockets from opposite ends of the same, a removable strip extending through slots in the bow-bends, and means for maintaining this latter strip in engagement with said bow-bends. 95

In testimony that I claim the foregoing I have hereunto set my hand at Milwaukee in the county of Milwaukee and State of Wisconsin in the presence of two witnesses.

EGMONT B. ARNOLD.

Witnesses:

GEO. W. YOUNG,
GEORGE G. FELBER.
